UNITED STATES PATENT OFFICE

135,917

DESIGN FOR A PROJECTOR HOUSING

William A. Lebus, Chicago, Ill., assignor to Prismacolor, Inc., Chicago, Ill., a corporation of Illinois

Application November 9, 1942, Serial No. 108,725

Term of patent 14 years

To all whom it may concern:

Be it known that I, William A. Lebus, a citizen of the United States, residing at Chicago, in the county of Cook and State, of Illinois, have invented a new, original, and ornamental Design for a Projector Housing, of which the following is a specification, reference being had to the accompanying drawings, forming a part thereof.

In the drawings:

Fig. 1 is a front view of a projector housing showing my new design;

Fig. 2 is a rear view of the projector housing shown in Fig. 1;

Fig. 3 is a plan view of the projector housing;
Fig. 4 is a side elevational view of said housing as viewed from the right side in Fig. 1; and
Fig. 5 is a side elevational view of the housing as viewed from the left side in Fig. 1.

The film reels and supporting arms therefor, shown in broken lines in Figs. 4 and 5, have been omitted in the other figures for convenience of illustration.

I claim:

The ornamental design for a projector housing, as shown.

WILLIAM A. LEBUS.
